CLAIM

The ornamental design for a watch case, as shown and described.

DESCRIPTION

FIG. 1 is a front view of a watch case, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof.

FIG. 8 is an enlarged view of a portion labeled 8 in FIG. 1;

FIG. 9 is an enlarged view of a portion labeled 9 in FIG. 1; FIG. 10 is an enlarged view of a portion labeled 10 in FIG. 2;

FIG. 11 is an enlarged view of a portion labeled 11 in FIG. 2;

FIG. 12 is an enlarged view of a portion labeled 12 in FIG. 3;

FIG. 13 is an enlarged view of a portion labeled 13 in FIG. 4; and,

FIG. 14 is an enlarged view of a portion labeled 14 in FIG. 7.

The broken lines in the drawings depict portions of the watch case that form no part of the claimed design.

1 Claim, 14 Drawing Sheets
